UNITED STATES PATENT OFFICE.

AUGIE L. HANSEN, OF EVANSTON, ILLINOIS, ASSIGNOR TO JUSTRITE MANUFACTURING COMPANY, OF CHICAGO, ILLINOIS, A CORPORATION OF ILLINOIS.

BURNER-TIP FOR ACETYLENE OR OTHER HYDROCARBON GASES.

1,280,214.

Specification of Letters Patent.

Patented Oct. 1, 1918.

Application filed May 18, 1917. Serial No. 169,447.

To all whom it may concern:

Be it known that I, AUGIE L. HANSEN, a citizen of the United States, and a resident of Evanston, in the county of Cook and 5 State of Illinois, have invented certain new and useful Improvements in Burner-Tips for Acetylene or other Hydrocarbon Gases, of which the following is a specification.

My invention relates to an improved 10 burner tip for acetylene gas or hydrocarbon gas which is so constructed as to become sufficiently heated during burning of the gas to effect re-ignition of the gas after extinguishment of the flame. In my co-pending 15 application Serial No. 133,315, filed November 25, 1916, I disclose a burner tip constructed to effect re-ignition of the gas, the tip comprising a base with a fine orifice for projecting a tongue of gas, and a frame part 20 having an enlarged bore or chamber for receiving the gas and having a restricted outlet from which the illuminating flame projects, the frame prolonging and surrounding the blue zone of the flame and the restricted 25 outlet causing such baffling or retardation as will cause the blue flame to be in intimate engagement with the material, particularly at the end of the chamber, thereby to so highly heat the frame end that if the flame is 30 extinguished, the gas flowing through the frame will be immediately re-ignited. The tip structure shown in the co-pending application is formed of a single piece of refractory material which makes it difficult and 35 impractical to bore or drill the various bores of different diameters, the bores or openings of smallest diameter being at the ends.

The object of the invention of the present 40 application is to produce a more practical tip structure, that is, one in which the various bores can be more practically and readily made. In accordance with my invention the tip structure is of two parts, namely, a base part constructed to project a pencil of gas 45 or flame, and a frame part adapted to be secured to the base, this construction greatly facilitating the manufacture of the tip structure.

A tip structure embodying my invention 50 is shown on the accompanying drawings, in which—

Figure 1 is a side elevational view;

Fig. 2 is an outer end view;

Fig. 3 is a sectional view on plane 3—3, 55 Fig. 1, and

Fig. 4 is a sectional view on plane 4—4, Fig. 1.

The tip structure comprises the base part B and the frame part F, both preferably constructed of refractory material such as 60 so-called lava. The base has the conical inner end section 10 and the cylindrical outer end or head 11 separated from the conical inner end by the annular cylindrical flange 12. In the end 10 is the gas entrance 65 chamber 13 and in the head 11 is the gas outlet chamber 14, a partition 15 separating the chambers except for the fine central orifice 16. Radial air ducts 17 lead to the inner end of the outlet chamber 14, the incoming 70 air mixing with the gas in this chamber. By means of the conical end 10 the base B may be seated directly in the end of a gas pipe or in a metallic bushing (not shown) which is seated in the gas pipe. 75

The frame F is a cylindrical shell comprising the outer more inclosed section f and the inner more open section f'. The lower end of the frame is of a diameter to receive the head 11 of the base and to seat 80 on the flange 12, and the frame may be secured to the base as by means of cement c. At the outer end of the frame is the inner annular flange 18 surrounding the central outlet 19 which is shown as of considerably 85 less diameter than the interior of the frame, the flange 18 serving as a means to baffle and retard the blue flame whereby to cause such flame to be in intimate association with the end of the frame to highly heat it so that 90 when the flame is extinguished the gas will be re-ignited. By having the base B and frame F separable the various bores and orifices in the base can be more readily made, and the drilling or boring of the cylinder to 95 form the frame F with its contracted outlet 19 can also be more readily accomplished. After formation of the parts B and F they can be readily secured together.

The base B is in itself a burner tip from 100 which gas issues to burn in a long pencil with an inner blue non-carbonizing zone and an outer illuminating zone, but the gas would not be re-ignited after extinguishment of the flame. By applying the frame 105 F the blue zone will be encircled and prolonged, the hottest part being in the outer section f where the blue flame is baffled, retarded and caused to form eddies by the flange 18, and to increase the heat retaining 110

capacity the annular enlargement or head 20 is provided at the frame end to increase the bulk of material thereat, which material will be highly heated and will hold the heat for some time so that if the flame is extinguished the gas will be re-ignited. A number of small outlets 21 may also be provided in the section *f* just inside the flange and bead so that tongues of blue flame can be projected outwardly to lick the outside surface of the frame end.

The inner section *f'* of the frame by seating on the base B serves to hold the re-igniting end section *f* a suitable distance away from the base outlet, and this lower section is more or less open for admitting air into the section *f*. Sufficient opening may be provided by longitudinally slotting or slitting the section *f*, or, as shown, air holes 22 may be drilled through the walls of the section *f'*.

The advantages of my two-piece tip structure can be more fully realized if it is understood that burner tips, particularly the small tips for miners' acetylene cap lamps, are made by turning and boring solid pieces of soapstone or so-called lava in its natural state when it is soft and fragile, the tip after the turning and boring operation being baked and hardened. In working on the raw, soft and fragile material great care must be taken, particularly during the boring and drilling operations to form the various communicating passageways, chambers, or orifices of different diameters. With my construction, where the base and frame are made separate, boring and drilling can be accomplished in a more practical and safe manner.

40 I do not desire to be limited to the exact constructions shown as modifications can probably be made which would still come within the scope of the invention.

I claim as follows:

45 1. A burner tip for acetylene or other hydrocarbon gas consisting of a base part and a frame part, said base part being adapted for insertion in a gas conducting pipe and having an axial restricted orifice for projecting a stream of gas under pressure, said frame part extending from said base part and being open at its inner section to the inflow of gas and air, the outer section of said frame having restricted outlet passageway for gas and encircling and retarding the blue part of the flame when the gas is ignited to be heated by the retarded blue flame to a temperature which will cause re-ignition of the gas flowing through the gas outlet passageway after the gas is extinguished.

60 2. A burner tip for acetylene or other hy-

drocarbon gas consisting of a base part and a frame part, said base part being adapted for insertion in a gas conducting pipe and having an axial restricted orifice for projecting a stream of gas under pressure, said frame part seating at its inner end on said base part and open at its lower section to the inflow of gas and air, the outer section of said frame having restricted outlet passageway for gas and forming a chamber for encircling and retarding the blue part of the flame when the gas is ignited to be heated by the retarded blue flame to a temperature which will cause re-ignition of the gas flowing through the outlet passageway after the flame is extinguished.

3. A re-igniting burner tip for acetylene or other hydrocarbon gas consisting of a base part and a frame part, said parts being formed separately, said base part being adapted for connection with a gas conductor and being provided with an axial restricted orifice through which a stream of gas is projected under pressure, said frame part comprising an outer section and supporting means for engaging with the base part to position said outer section at a determined distance away from the base part orifice outlet, said end section encircling the blue zone of the flame when the gas is ignited, and means in said outer section for baffling and retarding the blue flame in order to be intimately engaged by said blue flame to be raised thereby to a temperature which will cause re-ignition of the gas after extinguishment of the flame.

4. A re-igniting burner tip for acetylene or other hydrocarbon gas consisting of a base part and a frame part, said parts being formed separately, said base part being of circular cross-section and having a restricted axial gas orifice therethrough for projecting a stream of gas under pressure, an annular flange surrounding said base part intermediate its ends, said frame part being a cylindrical shell seating at its end on said flange and around the outer end of said base part, the inner section of said shell being open to the atmosphere, the outer section of said shell encircling and inclosing the gas stream and having an axial outlet of restricted diameter for the stream, said outlet restriction resisting the gas flow and causing the blue flame part of the ignited gas to be in intimate contact with said outer section of the shell whereby to heat such section to a temperature which will cause re-ignition of the gas stream after extinguishment of the flame.

In witness whereof I hereunto subscribe my name this 7th day of May, A. D., 1917.

AUGIE L. HANSEN.
